CLAIM

I claim the ornamental design for a forward grip laser sight, as shown and described.

DESCRIPTION

This application is related to U.S. Design patent application Ser. No. 29/609,437, filed Jun. 30, 2017, the disclosure of which is incorporated by reference herein.

This application is related to U.S. Design patent application Ser. No. 29/610,906, filed Jul. 17, 2017, the disclosure of which is incorporated by reference herein.

FIG. 1 is a perspective view of the forward grip laser sight.

FIG. 2 is a perspective view of the forward grip laser sight.

FIG. 3 is a perspective view of the forward grip laser sight.

FIG. 4 is a perspective view of the forward grip laser sight.

FIG. 5 is a perspective view of the forward grip laser sight.

FIG. 6 is a perspective view of the forward grip laser sight.

FIG. 7 is a perspective view of the forward grip laser sight.

FIG. 8 is a perspective view of the forward grip laser sight.

FIG. 9 is a left side view of the forward grip laser sight of FIG. 1.

FIG. 10 is a front view of the forward grip laser sight of FIG. 1.

FIG. 11 is a top view of the forward grip laser sight of FIG. 1.

FIG. 12 is a right side view of the forward grip laser sight of FIG. 1.

FIG. 13 is a rear view of the forward grip laser sight of FIG. 1; and,

FIG. 14 is a bottom view of the forward grip laser sight of FIG. 1.

Broken lines shown in the drawings form no part of the claimed design.

We understand that the embodiments of our inventions includes features and components illustrated by the drawings herein and shown in the applications incorporated by reference, in all permutations and combinations of such components and features. In other words, we understand embodiments our inventions include the discrete components illustrated by the drawings herein and the applications incorporated by reference, with or without specific features in the various drawings claimed. We understand embodiments of our inventions includes different combinations of such discrete components as illustrated by the drawings herein and in the applications incorporated by reference. Whereby we reserve the right and contemplate making solid lines dashed for any specific feature or component, part, or portion in the various embodiments illustrated herein and in the drawings of the applications incorporated by reference herein as we have contemplated such as being embodiments

(Continued)

of our invention, and we reserve the right and contemplate making dashed lines solid for any specific feature or component, part, or portion.
